DESIGN FOR AN EMBROIDERED SCARF OR SIMILAR ARTICLE

Elmer R. Goldsmith, New York, N. Y.

Application August 5, 1941, Serial No. 102,694

Term of patent 3½ years

To all whom it may concern:

Be it known that I, Elmer R. Goldsmith, a citizen of the United States of America, residing in New York city, county of New York, and State of New York, have invented a new, original, and ornamental Design for an Embroidered Scarf or Similar Article, of which the following is a specification, reference being had to the accompanying drawing, forming part thereof, wherein, the figure is a plan view of an em-

broidered scarf or similar article, showing my new design, the same being depicted on a dark background for the purpose of bringing out more clearly the details thereof.

I claim:

The ornamental design for an embroidered scarf or similar article, substantially as shown and described.

ELMER R. GOLDSMITH.
